Attorney

UNITED STATES PATENT OFFICE.

JAMES SCULLY AND WILLIAM B. MCCOY, OF SULLIVAN, INDIANA.

ATTACHMENT FOR HOOD CLAMPS OF AUTOMOBILES.

Application filed March 8, 1922. Serial No. 542,033.

To all whom it may concern:

Be it known that we, JAMES SCULLY and WILLIAM B. MCCOY, citizens of the United States of America, and residents of Sullivan, in the county of Sullivan and State of Indiana, have invented certain new and useful Improvements in Attachments for Hood Clamps of Automobiles, of which the following is a specification.

10 This invention relates to hood retaining devices for automobiles, the said invention having for an object the provision of novel means adapted to be attached to the ordinary equipment of a well known make of automobile, for facilitating the application and removal of the hood clamps, the said invention being adapted to be applied to the heads of clamps now in common use to present a hand-hold which will facilitate the manipulation of clamps of this character.

As is well known, the hood clamps usually employed in automobiles include spring held shanks terminating in heads adapted to engage a flange or bead of the hood. In 25 certain types of machines, the head is of such restricted area as to render it difficult to secure a firm hold and the operation becomes laborious and difficult.

By the present invention, a projection or horn-like structure is formed as a part of a plate adapted to be secured to a head of a clamp of the character indicated, so that by a comparatively inexpensive attachment, the manipulation is facilitated as stated.

35 With the foregoing and other objects in view, the invention consists in the details of construction, and in the arrangement and combination of parts to be hereinafter more fully set forth and claimed.

40 In describing the invention in detail, reference will be had to the accompanying drawings forming part of this application wherein like characters denote corresponding parts in the several views, and in which—

45 Figure 1 illustrates a perspective view of a fragment of an automobile hood, showing a device embodying the invention applied thereto;

Figure 2 illustrates an enlarged detail 50 view of a clamp and a device embodying the invention applied thereto;

Figure 3 illustrates a front view thereof with the spring omitted;

Figure 4 illustrates a sectional view;

55 Figure 5 illustrates a plan view of one of the elements; and

Figure 6 illustrates a plan view prior to its being bent.

In these drawings 10 denotes an automobile hood, 11 the head of a clamp with 60 seats 12 adapted to engage the bead or flange 13 of the hood. The head has a shank 14 encircled by a spring 15 which is effective to exert downward pressure on the head to hold it in firm contact with the bead of the automobile hood. 65

The device which is intended to be applied to the head, in the present embodiment of the invention, comprises an apertured plate 16 which might be termed the 70 "backing plate" and this is preferably stamped and shaped to form a curved flange 17 at one edge that conforms to the contour of the head, it being understood that the head is apertured, as shown at 18, to receive 75 the fingers of an operator. The plate 16, however, covers practically the entire face and aperture of the head and it preferably has a central seat 19 in which a nut 20 will lie. The seat is preferably of such configuration as to constitute an abutment for the nut to prevent its turning, so that when the bolt 21 is applied to the nut, the said nut will not rotate, and this provision also prevents the nut from backing off the bolt 80 when in use. 85

The backing plate coacts with what might be termed a "face plate" 22 which fits on the outer face of the head and this plate 22 has an integral handle or horn-like projection 23 which may be grasped by an operator for lifting the head into engagement with the flange, or for removing it therefrom. 90

It will be seen from an inspection of the 95 drawing that the backing plate and face plate may be formed by the ordinary stamping processes, since they may be cut from sheet metal and then bent to appropriate shape, the plates 16 and 22 being provided with 100 apertures 24 and 25 respectively which receive the bolt 21.

The devices may be cut and shaped by the ordinary stamping processes, as stated, and therefore, the cost will be comparatively 105 small.

The edge of the plate 22 that engages the edge of the handle is shaped similarly to the flange 17, so that when the plates are assembled, they will fit the contour of the 110 head and when the bolt is applied through the plates, dislodgment of the said plates

with relation to the head and with relation to each other will be avoided.

We claim:

1. In an attachment for hood clamps of automobiles, the combination with the head of a clamp, a plate applied to one side of said head, a plate having a handle applied to the other side of said head, and means extending through the plates for clamping them on the head.
2. In an attachment for hood clamps of automobiles, a plate having an integral ex-

tension forming a handle, and means for securing the said plate to a clamp of a hood.

3. In an attachment for hood clamps of automobiles, a plate having a horn-like extension forming a handle, a plate constituting a backing plate coacting therewith, and means extending through the two plates for pressing them into engagement with the said clamp.

JAMES SCULLY.
WILLIAM B. MCCOY.
